Atty's:

UNITED STATES PATENT OFFICE

94,711

DESIGN FOR A LEG FOR A STOVE OR SIMILAR ARTICLE

Walter F. Rogers, Cicero, Ill., assignor to Crown
Stove Works, Cicero, Ill., a corporation of
Illinois

Application January 12, 1935, Serial No. 54,833

Term of patent 3½ years

To all whom it may concern:

Be it known that I, Walter F. Rogers, a citizen of the United States, residing at Cicero, county of Cook and State of Illinois, have invented a new, original, and ornamental Design for a Leg for a Stove or Similar Article, of which the following is a specification, reference being had to the accompanying drawing, forming a part thereof.

Fig. 1 is a perspective of the new leg for a stove or similar article.

Fig. 2 is a side elevation of the same.

I claim:

The ornamental design for a leg for a stove or similar article substantially as shown.

WALTER F. ROGERS.
